UNITED STATES PATENT OFFICE

RICHARD F. GREENWOOD, OF NEW YORK, N. Y.

RAILROAD TIE OF COMPOSITE REINFORCED CONCRETE

Application filed December 18, 1929. Serial No. 414,915.

This invention relates to improvements in composite railroad ties.

One of the objects of my invention is to produce a composite railroad tie of reenforced concrete which will to a maximum degree provide the strength and power necessary to withstand the shattering and crushing forces of traffic, which can be produced for a cost which will make its use economical, 10 which will serve the function of an efficient rail support adapted to hold the rail uniformly to gage, will eliminate the use of tie plates and like devices and will be capable of ready handling.

Another object of my invention is to produce a tie of the block and bar type in which there is embedded beneath each rail a separate or independent metallic element having in itself alone great load-carrying 20 strength and providing in the complete tie the tensile strength of the metallic element while avoiding the danger of center binding.

Another object of my invention is to provide in a block or section of a railroad tie 25 formed of a plurality of sections connected by a metal bar and known as ties of the block and bar type, a combined rail support and embedded reinforcement which will have sufficient load carrying strength alone to support a major portion or all of the load which will normally be carried by the tie.

Another object of my invention is the provision in a concrete railroad tie, preferably of the type hereinabove specified, of a unitary rail-supporting and reinforcing element 35 for each block or section comprising an open-work base portion of substantially the area in outline of the concrete block and a rail-supporting portion preferably of inverted trough or channel shape disposed transversely of the axis of the tie and beneath the rail and preferably extending on opposite sides of the normal outer edges or sides of the tie.

Still another object of my invention is the provision, in each block or section of a railroad tie of the block-and-bar type hereinabove specified, of a combined rail-supporting and concrete reinforcing element composed of a single piece of metal and prefer-

ably composed of a single metal casting or forging, which will alone have high tensile and load-carrying strength, whereby I am enabled through the connection by a metallic bar of such elements in opposite blocks or 55 rail-supporting sections to develop in the complete tie the high tensile and load-carrying strength of the metallic reenforcing elements and consequently to produce greatly increased strength in the composite metal 60 and concrete tie.

Still another object of my invention is to provide in a composite tie preferably of the block-and-bar type hereinabove specified, a block of concrete or like material having embedded therein a combined rail-supporting and concrete reenforcing element composed of a single piece of metal comprising a rail-supporting portion and a base portion therefor composed of truss elements, said rail-supporting portion preferably being composed of an inverted trough or channel disposed transversely of the longitudinal axis of the tie and provided in its opposite flanges with mounting apertures for movable rail-fastening members supported adjacent to their opposite ends, and said base portion comprising open-work truss-members arranged to reinforce and strengthen the rail-supporting portion and the concrete block in 70 which it is embedded, these truss-members also forming extension arms to enable the transmission, when opposite blocks are connected together, of strains of tension and the distribution of load to the complete tie. 75

Still another object of my invention is to utilize, in connection with a combined concrete reenforcing and rail-supporting element composed of one piece, an integral rail-fastening member and preferably an integral 90 rail-fastening hook engaging the outside edges of the rail flanges whereby the combined rail-supporting and concrete reenforcing elements in the blocks or rail-supporting sections when connected together by a metallic connecting rod will perform the additional function of a track-clamping element or tie-bar of great strength and will maintain the gauge of the tracks or rails and prevent any spreading of the rails in use. 95

Still another object of my invention is to provide, in a tie construction of the character specified, means for insulating the opposite reenforcing elements from each other to enable the use of a tie in location where track circuits are involved and for this purpose, I preferably provide in the joint between the integral reenforcing elements in each block and the bar a block or disc of fibre-insulating material which will positively insulate the opposing rails from each other.

With these and other objects in view, the invention comprises the combination of members and arrangement of parts so combined as to co-act and co-operate with each other in the performance of the functions and the accomplishment of the results herein contemplated, and comprises in one of its adaptations the species or preferred form illustrated in the accompanying drawings, in which:—

Fig. 1 is a plan view of a composite railroad tie of the block-and-bar type combining my invention, one of the blocks showing a rail mounted thereon and the other showing the rail demounted with the metallic skeleton in dotted lines;

Fig. 2 is a side elevation of the railroad tie shown in Fig. 1;

Fig. 3 is a section on the line 3—3 of Fig. 1;

Fig. 4 is a section on the line 4—4 of Fig. 1; and

Fig. 5 is a plan view of the cast-metal skeleton embodied in each of the blocks and shown in Figs. 1 and 2.

Referring now to these drawings, which illustrate a preferred embodiment of my invention 1, 1 indicate the opposite concrete blocks of a railroad tie of the block-and-bar type and 2 indicates the bar connecting the blocks 1, 1.

In accordance with my invention, a metallic skeleton 3 (see Fig. 5) of unitary character is embedded in each of the blocks 1, 1, and an important part of my invention resides in providing in each block, section or head of the railroad tie on which a rail is supported, a metallic skeleton which has the double function of providing a solid and rigid support for a rail and of providing a strong reinforcement for the concrete block in which it is embedded. Preferably my combined reenforcement and rail-support has a metallic base member of relatively broad area preferably conforming in extent and outline with the concrete block and an effective metallic rail-seating member, and the combined members or skeleton has sufficient load-carrying strength alone to support a major portion or all of the load which will

normally be carried by the block or section of the railroad tie. In the preferred form of my invention, I utilize a skeleton composed of a single piece and preferably comprising a metal casting or forging having integrally formed therein an inverted trough-shaped

rail-seating portion 4 and a base portion 5 comprising open-work trusses 5' extending laterally on opposite sides thereof.

In the preferred form of my invention illustrated, the rail-seating portion 4 comprises an inverted trough or channel member open at its bottom, extending transversely of the longitudinal axis of the tie and embodying a horizontal web or rail seat 4' and downwardly-extending vertical flanges 4", and I mount on this rail-seating member 4 fastening devices for engaging and retaining the rail in position thereon.

In the said preferred form of my invention, the flanges 4" of the rail-seating member are provided on the opposite sides of the axis of the tie with apertures 6, 6' and 7, 7' in which apertures are mounted movable hook bolts or fastening elements 8, 8'. One side of the rail flange is preferably engaged by a stationary rail-engaging hook 9 disposed across the longitudinal axis of the tie, and hook bolts 8, 8' are each mounted in said opposing flange apertures and are both utilized to engage the other side of the rail-flange and to clamp one flange to the rail-seat, and to force the opposite rail-flange into wedging contact between the stationary hook and the rail-seat. In the said preferred embodiment of my invention illustrated, the stationary hook 9 is formed integrally with the skeleton casting and preferably is disposed at the outer side edge thereof so as to overhang the upper surface of the web-portion 4' of the rail-seating member 4. This hook 9 is preferably reenforced and strengthened by three vertical ribs 9', 9" and 9" which extend downwardly and merge with the outwardly-extending trusses of the base-portion 5" 5' the bottom of which trusses preferably extend in a horizontal plane substantially coinciding with the lower edge of the flanges of the rail-seating member 4.

In the preferred form of my invention illustrated, the truss bars of the base portion extend on opposite sides of the rail-seating member 4 and are symmetrically arranged to extend from the middle and ends of the lower edges of the flanges outwardly in opposite directions to the longitudinal axis of the railway tie, the truss bars on each side preferably comprising open-work curved members 5", and 5" which are so curved and arranged as to reinforce the corners formed between the main body B of the block and lateral extensions E thereof and these truss bars also preferably include a vertically disposed reinforcing bar 5" which extends substantially along the longitudinal axis of the block.

The base member 5 of each block 1 is preferably provided with a vertical aperture 10 and in cases where my railroad ties are laid in track sections which involve electric circuits, I preferably mount in each of the apertures 10 a disk 11 of suitable insulating ma-

5 terial, such as insulating fibre, and each of these disks will be provided with a vertical bore or aperture 12 adapted to receive a downwardly-projecting hook-portion 13 of the connecting bar 2 which is utilized to connect opposite rail-seating blocks 1 and in the preferred form of my invention is connected thereto by passing the downwardly-disposed hooks 13 through the apertures 12.

10 It will be seen that when the skeleton members are so connected by the connecting bar 2, strains of tension will be transmitted from the metallic skeleton in one block to the metallic skeleton in the other.

15 It will be seen from the above that I have provided a unitary metallic element preferably formed of a single metallic casting or forging, which in itself alone will have load-carrying strength of very high degree and in most cases will have sufficient load-carrying strength alone to support a major portion or all of the load which will normally be carried or imposed upon the block in which the skeleton is embedded.

20 25 As illustrated, the aforesaid skeleton is embedded in a block of concrete 1 of substantially similar length and width of the skeleton and is preferably of the thickness to extend substantially below the flanges of the rail-seating member 4 and the bottom of the truss bars of said base portion, the upper surface of the concrete block being flush with the outer surface of the web or rail-seat portion 4' of the rail-seating member 4 with the hook 9 extending above and overhanging said web and also projecting above said concrete surface.

30 35 In the said preferred form of my invention illustrated, the concrete block adjacent to the bolts 8, 8' is reduced in thickness to provide a depressed water-shedding surface portion 15, 15', 16, 16' at opposite ends of the rail-seating member 4, so as to enable the insertion within the apertures 6, 6', and 7, 7' of the hook bolts 8, 8', to permit manipulation of the ends of these bolts for the purpose of tightening up the ends of the hooks on the flanges f of the rail R, and to provide for drainage.

40 45 A bar-seating notch 17 is also formed in the upper portion of the concrete block and extends from the aperture 10 outwardly so as to permit the insertion downwardly of the hooks 13 of the bar 2 into the apertures 12 to connect the opposite blocks and to also provide a connection between the skeleton members of these blocks which will positively cause the transmission of strains from the block and skeleton which support one rail to the block and skeleton which supports the opposite rail.

50 55 Obviously these connecting bars will be useful in gauging the position of the concrete blocks 1 and in maintaining the gauge between the rails.

60 65 It will also be seen from the above that I have provided a railroad tie construction in which metallic skeletons, having a high degree of tensile strength will, when combined with a heavy connecting bar, in effect form tie bar elements adapted to lock the opposite rails in properly spaced relationship to each other and to prevent any spreading thereof.

70 75 It will be seen, furthermore, that I have provided a tie construction in which the reinforcing metallic skeleton not only has great independent load-carrying strength but when embodied in the concrete block will provide a reinforcement for all portions of the block; that by the use of my ties, I am enabled to provide ties of much greater rigidity than the wooden ties now generally employed, that I provide fastenings which hold the rails securely on the ties and thus reduce wave-motion substantially and enable the production and maintenance of tracks in substantially perfect horizontal alignment.

80 85 Having described my invention, I claim:—

90 95 1. A composite railroad tie, embodying, in combination, a pair of concrete rail-supporting sections, each section having embedded therein a unitary metallic element of substantially the horizontal area of the section and comprising a single metallic casting having integrally formed a rail-seating member provided with an integral hook mounted at the top and overhanging said rail-seating member, a base for said rail-seating member composed of truss bars extending laterally from the bottom edge of said rail-seating member, said members being so arranged as to provide effective reinforcement for said concrete section, and a metallic connecting bar arranged to connect the base members of opposite metallic elements to produce a complete railroad tie having high tensile and load-carrying strength.

100 105 110 115 120 125 2. A composite railroad tie, embodying, in combination, a pair of concrete rail-supporting sections, each section having embedded therein a single metallic casting having integrally formed an inverted oblong trough provided at its top surface with an integrally formed stationary hook for engaging a rail flange and having in its sides mounting apertures for movable fastening elements, movable rail-fastening hooks mounted in said apertures for engagement with the opposite flange, and metallic elements for connecting opposite inverted troughs in said rail-supporting sections, said metallic elements being arranged to transmit strains of tension from one metallic trough and integral hook to the other.

130 3. In a composite railroad tie, comprising a concrete rail-support having embedded therein a unitary metallic element composed of a single metallic casting having integrally

formed a rail-seating member provided with an integral hook mounted at the top and overhanging said rail-seating member, and a base for said rail-seating member extending outwardly therefrom and so arranged as to provide effective reenforcement for said concrete support.

4. In a composite railroad tie, comprising a concrete rail-support having embedded therein a unitary metallic element composed of a single metallic casting having integrally formed a rail-seating member provided with an integral hook mounted at the top and overhanging said rail-seating member, a base for said rail-seating member extending outwardly therefrom and so arranged as to provide effective reenforcement for said concrete support, and movable hook members mounted in said metallic casting beneath the rail-seating member to engage the side of the rail opposite to said integral hook and to cooperate therewith in fastening a rail to said support.

5. In a composite railroad tie, a concrete rail-support having embedded therein a single metallic casting having integrally formed an inverted oblong trough provided at its top surface with an integrally formed stationary hook for engaging a rail flange at one side of a rail and having in its sides below said top surface mounting apertures for movable fastening hooks, and movable rail-fastening hooks mounted in said apertures for engagement with the flange at the opposite side of the rail.

In witness whereof, I have signed my name to the foregoing specification.

RICHARD F. GREENWOOD.
